J. A. YAHRES.

BELT SPLITTING DEVICE.

APPLICATION FILED NOV. 22, 1917. RENEWED FEB. 26, 1919.

1,307,290.

Patented June 17, 1919.

Jacob A. Lahres,

C.E. Humphrey Attorney

UNITED STATES PATENT OFFICE.

JACOB A. YAHRES, OF AKRON, OHIO.

BELT-SPLITTING DEVICE.

1,307,290.

Specification of Letters Patent. Patented June 17, 1919.

Application filed November 22, 1917, Serial No. 203,383. Renewed February 26, 1919. Serial No. 279,417.

To all whom it may concern:

Be it known that I, JACOB A. YAHRES, a citizen of the United States, residing at Akron, in the county of Summit and State of Ohio, have invented new and useful Improvements in Belt-Splitting Devices, of which the following is a specification.

This invention relates to improvements in devices for trimming, splitting, or longitudinally dividing a continuous article, such for instance as a belt or strip of flexible material.

The object of the invention is to provide a simple and effective device for longitudinally splitting, or trimming a belt or strip of flexible material passed therethrough and is especially designed for splitting strips of leather belts into strips, although its function is not thereby limited to such use.

More specifically the invention embodies mechanism by the use of which a continuous or substantially continuous strip of material, such as a leather belt may be split, divided or trimmed longitudinally into a plurality of separate strips, easily and economically and by the use of which the edges or sides of the severed or split away sections of the original article are parallel with one of the sides of the original strip.

Furthermore the invention contemplates the provision of a simple machine by which a strip of material may be divided, split or trimmed; said machine embodying adjustable means for controlling the transverse width of the portions, cut, severed or divided from the original or initial strip, said means comprising a cutting or trimming tool in association with a guide for the strip of material, and means to shift the position of said guide with respect to said cutting tool whereby the widths of the severed sections may be easily predetermined.

With the foregoing and other objects in view, the invention consists in the novel construction, combination and arrangement of parts, constituting the invention to be hereinafter specifically described and illustrated in the accompanying drawings, which form a part hereof, wherein is shown the preferred embodiment of the invention, but it is to be understood that changes, variations and modifications, may be resorted to which come within the scope of the matter herein-after claimed.

In the drawings in which similar reference numerals indicate like parts in the different figures,

Figure 1, is a perspective view of the machine embodying the present invention.

Fig. 2, is a plan view of the device, shown in Fig. 1.

Fig. 3 is a sectional view taken approximately on line 3 of Fig. 2.

Referring to the drawings in detail, the device embodies a frame comprising side members, 1 and 2, arranged in parallelism and connected at their ends by end-bars 3 and 4. The members 1-4 are all preferably formed integrally and depending from the member 1 is a bracket 5, provided with openings 6 through which may be passed holding members such as bolts for securing the device to some fixed instrumentality, such for instance as a bench. Extending upwardly from the end member 4 is a support 7 provided with a bifurcated upper end and extending upwardly and preferably formed integrally with the end member 3 is a support 8, similar to the support 7 and provided with a bifurcated end. Secured in the slots formed by the bifurcations in the supports 7 and 8 is a guide rod 9 provided with graduations 10. The guide rod 9 is secured at its ends in the supports 7 and 8 by means of holding members such for instance as pins 11.

Positioned immediately below the opening in the upright 8, in the end member 3 is a socket 12, constituting a bearing, and in the member 4 is a bearing 13 which is in exact alinement with bearing 12 and in vertical alinement with the guide bar 9. The bearings 12 and 13 constitute supporting means for a threaded shaft 14 which is mounted therein, one end of which is formed to seat in the bearing 12, and with the opposite end cylindrically fastened to be seated in the opening in the bearing 13. The intermediate portion of the shaft 14 is provided with screw threads 15 for a purpose to be later described. The shaft 14 is held from longitudinal movement by means of a collar 16, mounted on the shaft 14 adjacent to the bearing 13 and this collar 16 is held in place by means of a cotter pin 17. Outside of the end member 4 the shaft 14 is provided with an operating head 18, preferably provided with a knurled edge.

5 Mounted on the threaded portion of the shaft 14 is a guide 19 preferably in the form of a cylindrical wheel, one portion of which has a radial slot 20 which receives the guide bar 9 and is provided with a central opening which is interiorly threaded to receive the shaft 14, so that when the male threads of the shaft 14 are rotated through the medium of the head 18, the guide 19 is shifted 10 longitudinally of the shaft 14, due to the engagement of the female threads in the member 19. The guide 19 is of such diameter as to partially inclose the guide bar 9, and the side faces of said guide 19 indicate 15 on the guide bar 9 the desired position of the guide 19 on the guide bar 9.

20 The side bar or member 2 is provided with an outwardly projecting lug 21, provided with an aperture in which is mounted a cap screw 22. Secured by means of the cap screw 22 to the inner face of the side bar 2 is a tool holder 23, comprising a base 24 and a pair of outwardly and horizontally projecting converging arms 25, the outer 25 ends of which are provided with alined openings to receive a clamping bolt 26. Arranged to be held in position by the tool holder 23 is a cutting tool 27, which is provided with an opening through which passes 30 the clamping bolt 26, and which is secured in position thereby. The cutting tool 27 is arranged to extend from the guide bar 9 downwardly below the shaft 14. In order to steady the upper end of the cutting tool 35 27 there is provided a notched lug 28, on the appropriate face of the guide bar 9, and so positioned that the edge of the cut-

ting tool may be seated therein to hold the tool from lateral movement.

40 The strip to be split and designated by the reference numeral 29, is passed over the upper faces of the bars 1 and 2, and in contact with the guide 19 and during its passage, the strip is severed, cutting therefrom the desired portion 30, of a width equivalent 45 to the distance between the guide 19 and the cutting tool 27. It will of course be obvious that the distance between the cutting tool 27 and the guide 19 may be varied by rotating the shaft 14 through the medium 50 of the head 18, and hence a strip 30 of any desired width may be produced from the initial strip 29.

I claim.

55 A device of the class designated embodying a frame comprising side and end members, a guide bar mounted on said end members, a lug on said guide bar provided with a notch extending transversely to said bar, a threaded shaft mounted in said end members, a guide shiftably mounted on said threaded shaft and provided with a slot to receive said guide bar, a tool-support connected with one side member of said frame, and a cutting tool mounted in said support 60 65 and disposed at an angle to said guide bar, and with a portion thereof engaging in the notch in the lug on said guide bar for holding said cutting tool against lateral movement.

70 In testimony whereof I have hereunto set my hand.

JACOB A. YAHRES.
